(57) **CLAIM**

The ornamental design for a fascia gun, as shown and described.

DESCRIPTION

Figure 1.1 is a perspective view of a fascia gun, showing my new design;

Figure 1.2 is a front view thereof;

Figure 1.3 is back view thereof;

Figure 1.4 is a left view thereof;

Figure 1.5 is a right view thereof;

Figure 1.6 is a top view thereof;

Figure 1.7 is a bottom view thereof; and

Figure 1.8 is a reference view thereof.

The additional elements shown in Figure 1.8 are for the purposes of illustrating environmental structure, which form no part of the claimed design.
